ROTARY MACHINE

Nils Nilsen Stræteit, Oslo, Norway

Application December 30, 1947, Serial No. 794,557
In Sweden December 31, 1946

7 Claims. (Cl. 103—131)

1

This invention relates to rotary machines having a piston that does not rotate about its own axis and that operates in a working space bounded by stationary end walls. The movement of the piston may for instance be such that all points on the piston move in circular orbits of equal radii.

Such a rotary machine may be used as compressor, as pump or as motor.

The main characterising feature of the present invention consists in that the transmission of power between the driving shaft and the piston is effected by means of organs rigidly secured to the piston at the ends of the latter.

In a preferred embodiment of the invention the power transmitting organs extend through one or more of the stationary end walls, but the invention is not restricted to such feature.

Suitably the power transmission organs may consist of pins or studs extending in parallel to the driving shaft through openings in the end walls of the working space and being, at the inner side of said walls, rigidly secured to the piston, and being each, exterior of said walls, connected to a disc that extends at right angles to the shaft and is rotatable on crank pins carried by the driving shaft.

Said openings in the end walls of the working chamber may suitably have circular cross section and be sealed by rotatable, disc-shaped sealing organs through which the power transmission organs extend. Such sealing organs then simultaneously may serve to guide the movement of the piston.

The invention will be more fully explained with reference to the drawing.

In the drawing:

Figure 1 is a sectional view of an embodiment, the section being taken on line I—I of Fig. 2 and

Figure 2 shows a section taken on line II—II of Fig. 1.

Figure 3 is a broken sectional view illustrating a modification of Figure 1.

Figures 4 and 5 are sectional views of another embodiment of the invention, the sections being taken on line IV—IV of Fig. 5 and on line V—V of Fig. 4, respectively.

Figure 6 is a vertical section of a detail on Fig. 4, on a larger scale, and

Figure 7 is a vertical section of a modification of said detail, whereas

Figure 8 is a side view corresponding to Fig. 7.

Figure 9 is a sectional view similar to Fig. 3 but shows still another embodiment.

The machine shown on Figures 1 and 2 com-

prises a housing 1 having two plane end walls 2 and 3 respectively, between which are provided two concentric cylinder walls, 4 and 5 respectively. Between said cylinder walls is confined the annular working chamber 6. The inlet 7 and the outlet 8 of the chamber 6 are provided in the outer cylinder wall 5. Between said inlet and outlet extends a radial wall 9, which separates the high pressure side from the low pressure side.

Within the annular working chamber 6 operates the piston 10. Also the piston is of annular shape but it is provided with an axial slot at the location of wall 9. This slot is necessary in order that the piston shall be able to move unhindered by wall 9. The piston is hollow and the thickness thereof is relatively great. On each end the piston is provided with four pins or studs 11. These are rigidly secured to the piston and extend through openings 12 in the end walls of the working chamber. Pins 11 are rigidly connected to discs 13 or 14 respectively. Said discs are journaled at 15 and 16 respectively on an eccentric shaft 17 mounted in the housing 1 by means of bearings 18 and 19. The piston 10 does not rotate about its own axis, but may, for instance, have such motion that all points on the same are moving in circular orbits the radii of which are equal to the eccentricity of the shaft.

Those portions of the openings 12 that are not at all times taken up by the pins 11 must be sealed off. In the embodiment illustrated on Figures 1 and 2 this is accomplished by giving the piston a thickness somewhat larger than the sum of extension of the pins or studs in radial direction and the eccentricity e of the shaft 17 multiplied by 4. The end faces of the piston then will act as sealing organs for the openings.

In the embodiment shown on Figure 3 the openings 12 are sealed by means of flanges 20 secured to the piston at the ends of the same. Said flanges are received in pockets 21 extending radially inwards from the working chamber 6, along the end walls 2 and 3 respectively. Apparently the flanges might as well extend radially outwards and be received in corresponding outwardly directed pockets, or the flanges might extend both outwards and inwards.

In the embodiment disclosed on Figures 4 and 5 the openings 12 are sealed by means of special sealing organs.

The openings 12 then suitably may be circular and the sealing organs consist of circular discs 22, each rotatably mounted in an opening. The pins 11 may extend through eccentrically ar-

ranged apertures 23 in the discs. By the use of a sufficient number of pins 11 the circular sealing organs may at the same time serve to guide the movements of the piston in such manner that all points on the piston move in circular orbits having radii equal to the eccentricity of the shaft.

Figures 6 and 7, 8 show, on a larger scale, details of such sealing organs.

On Figure 6 the aperture 23 through which a pin 11 extends has somewhat greater diameter than the pin, in order to avoid excessive friction. The pins are supposed to be rigidly connected to the piston 10, so that the pins will rotate relatively to the sealing organs 22. In order to obtain effective sealing in spite of the play between pin 11 and disc 22, there is provided a sealing disc 24 abutting against the edge portions of aperture 23 at one end thereof. Suitably the sealing disc 24 may be arranged countersunk in a cavity 25 milled in the disc 22.

Due to the play between pin 11 and disc 22 the construction just described does not provide for a fully effective guiding of the movements of the piston. Figures 7 and 8 illustrate how such guiding may become entirely effective. In the aperture 26, through which pin 11 extends, is placed a sleeve 27. Said sleeve has an opening 28 therethrough of extended cross section. The largest dimension of the cross section is greater than the diameter of stud 11, whereas the smallest dimension of the cross section is less than said diameter. The opening 28 has two parallel opposite side faces 29 and the pin 11 is shaped correspondingly, so that it may slide up and down within the opening 28, but cannot move transversely thereto. In the same manner as explained in connection with Figure 6 the pin 11 is also in Figure 7 provided with a sealing disc 24 placed in a cut-out 25 in the disc 22.

Above are described embodiments in which the power transmission organs extend through the stationary end walls of the working chamber. Even if this is considered the preferred form of the invention, a construction as illustrated on Figure 9 will also be possible. Here the power transmission organs 30 are arranged at the inner side of the end walls of the working chamber and extend through the inner wall 4 of the working chamber. The organs 30, which may have disc shape, are provided with apertures through which pass axially extending parts 32 connecting the inner wall 4 of the working chamber with the end walls 2 and 3 thereof.

I claim:

1. A rotary machine comprising a housing having spaced plane end walls, two spaced concentric cylinder walls secured between said plane end walls and forming therebetween an annular working chamber, the outer of said cylinder walls having an inlet and an outlet for said working chamber therethrough, an annular shaped piston in said working chamber having an axial slot therein, a radial wall extending between said plane end walls and from the inner of said cyl-

inder walls through said axial slot in said piston and having fluid tight contact with the outer cylinder wall between said inlet and said outlet, an eccentric shaft rotatably mounted in said housing, a disc journalled on said shaft externally to said housing at each end thereof, said end walls having openings therethrough adjacent said piston, pins rigidly connecting said discs and said piston extending through said openings in said end walls, said pins constituting means for transmission of power to or from said piston.

2. A rotary machine as claimed in claim 1, said openings through said end walls being elongated, said piston having a thickness greater than the openings in said end walls through which the power transmission pins extend, said pins being so arranged with respect to said piston and said discs that the piston end walls form sealing means for said openings in said end walls.

3. A rotary machine as claimed in claim 1, sealing flanges on said piston at the ends thereof extending at right angles to the machine axis and slidably co-acting with the openings in said end walls.

4. A rotary machine as claimed in claim 3, the inner of said concentric cylinder walls being offset adjacent the ends thereof to form pockets in said working chamber for receiving said sealing flanges.

5. A rotary machine as claimed in claim 1, said openings in said end walls being cylindrical, circular sealing discs inserted in said openings, said circular discs having eccentrically arranged apertures therethrough and said pins extending through said apertures in said circular discs, said circular discs constituting sealing organs for said machine, said sealing organs together with said pins serving as guiding organs for the movement of the piston.

6. A rotary machine as claimed in claim 1, said pins constituting means for transmission of power being cylindrical and extending parallel to the driving shaft and through said openings in the end walls of the working chamber, said pins being, at the inner side of said walls, rigidly secured to the piston and said disc being rigidly thereon, outside of said walls, at each machine side, said disc being rotatable on said eccentric shaft.

7. A rotary machine as claimed in claim 6, in which the diameters of said openings are greater than those of said pins, said pins carrying sealing discs resting against the edge portions of the openings on at least one side thereof.
